DAVID B. MARWICK, OF NEW BRITAIN, CONNECTICUT, ASSIGNOR OF ONE-HALF TO ETHELBERT A. MOORE, OF NEW BRITAIN, CONNECTICUT.

MACHINE FOR BUNDLING SCRAP.

No. 851,179.

Specification of Letters Patent.

Patented April 23, 1907.

Application filed December 12, 1905. Serial No. 291,408.

To all whom it may concern:

Be it known that I, DAVID B. MARWICK, a citizen of the United States, residing at New Britain, in the county of Hartford and State of Connecticut, have invented certain new and useful Improvements in Machines for Bundling Scrap, of which the following is a specification.

This invention relates to means for forming scrap into rolls or balls, and has for its object the provision of a machine by which the accumulated scrap may be readily withdrawn from the floor of a mill and coiled and consolidated into a compact portable ball or bundle, ready for any subsequent procedure desired.

A further object of the invention is the provision of a mandrel for winding the scrap, and in connection with said mandrel, a device cooperating therewith in the formation of said scrap into a consolidated mass, ready for transportation, or for admission into a reheating or melting furnace.

A further object of the invention is the provision of means whereby the device cooperating with the mandrel may be shifted to dislodge the compacted ball or mass from the mandrel.

A further object of the invention is the provision, in connection with the device for compacting and governing the formation of the ball or mass of scrap, of a tapered mandrel having means, for instance, a slot, in which the first strand of scrap may be inserted, the subsequent intermingled scrap being drawn forward by said first strand secured in any suitable way to said mandrel.

Other objects of the invention relate to details which will be hereinafter described.

In the accompanying drawings, Figure 1 is a plan view of a machine embodying my invention. Fig. 2 is a front elevation of said machine. Fig. 3 is a detail, partially in section, showing a ball of scrap in readiness to be discharged from the mandrel. Fig. 4 is a view, partially in section and in elevation, illustrating the mode of feeding the scrap in the formation of the ball, the section being taken on line 4—4 of Fig. 3, looking in the direction of the arrow. Fig. 5 is a longitudinal, horizontal section, taken on line 5—5 of Fig. 2, and Fig. 6 is a transverse section taken on line 6—6 of Fig. 5, looking in the direction of the arrow.

Like numerals designate similar parts, 55 throughout the several views.

Referring to the drawings, the numeral 1 designates a base provided with vertical posts or uprights 2, 3 and 4 in bearings of which the shafts of the machine are journaled.

In the bearing 2' of the post 2, is mounted a shaft 5 having a collar 5' located adjacent to the end of said bearing. Forward of this collar the shaft is extended to form a tapering mandrel 6 preferably of rectangular shape in 65 cross-section and provided with beveled corners 6', said mandrel being longitudinally grooved or slotted as at 7 for a purpose hereinafter described. Although shown integral with its shaft the mandrel may be detachably connected thereto, if desired.

While a mandrel of the particular shape shown is well adapted for the work to be accomplished, it is distinctly to be understood that the invention is not limited thereto, for 75 mandrels of other form may be employed, if desired.

At its rear end the shaft 5 is reduced at 5', and to the reduced portion is keyed or otherwise secured a gear 8.

Intermediate its ends the bearing 2' is provided with a flange 9, and forward of said flange it has a square or rectangular portion 10 (see Fig. 6), and is also provided with an externally-threaded cylindrical part 11, as 85 illustrated in Fig. 5. Threaded upon this part 11 of the bearing is a hub 12, having a groove 13 to receive the collar 5', and a reinforce or flange 14 at its inner end, and back of said flange the hub is of rectangular or box-like form externally, as shown in Fig. 6. Projecting from the flange 14, and shown as integral therewith, is a section 15 of a ring or yoke 16 for confining and compacting the bundle of scrap upon the mandrel, and articulated at 17 to said section 15 is the other half-section 18 of said yoke. An eye-bolt 19 is pivoted at 20 in a slotted lug 21 of section 15, and the shank of said bolt passes through the slot of a lug 22 of the part 18, a nut 23 locking the parts together, as shown in Fig. 2. In the median part of section 18 is formed a socket or bearing 24 to receive and support a cylindrical tip 25 of the mandrel 6 as shown in Fig. 5.

Fitted for sliding movement upon the hub 12 of the yoke and the bearing 2' is a rectangular sleeve 26, having a grooved flange

26', and surrounding said flange is a yoke 27, provided with studs 28 bearing blocks 29, traveling in the groove of said flange, and at its upper end the yoke 27 is provided with a handle 30, and at its lower extremity said yoke has an arm 31 pivoted at 32 to a bracket 33 secured to the inner side of the post or pillar 2.

Designated by 34 is the driving-shaft of the machine, said shaft being journaled in bearings of the uprights 3 and 4, and on this shaft is a belt-pulley 35 which may be clutched to the shaft when desired, or may run idly thereon. For connecting this pulley to the shaft a common form of friction-clutch may be employed, and pivoted levers 36, Fig. 1, constitute the means for operating said clutch. To actuate these levers a conical sleeve 37 is fitted loosely on the driving-shaft, and said sleeve may be actuated by a lever 38 pivoted at 39 to a bracket 40 projecting from the inner side of the upright 4. Any desired means may be employed, however, as substitutes for those shown and described for clutching the pulley to the shaft without departure from the invention.

Beyond the pulley the shaft is provided at its end with a pinion 41, in mesh with the gear 8 of the mandrel-carrying shaft 5.

Designated by 42 in Fig. 4 is a mass of intermingled scrap which is to be drawn from the floor or other support of the mill and to be wound upon the mandrel 6 into a roll or ball 43.

In the operation of the invention the first strands of this scrap are, in the construction shown, deflected at the end as at 44, Fig. 4, and are inserted in the slot 7 of the tapering mandrel 6, and after this has been done the pulley 35 is clutched to the shaft 34 by means described, or other devices employed as substitutes for said means, and the machine is set in operation.

As the mandrel revolves it will draw in and wind upon itself a mass of the interlaced and commingled scrap, and will form the same into a bundle 43. As shown the sections 15 and 18 of the yoke are shaped on their inner sides to a substantially elliptical contour, and these sections as the mass of scrap accumulates on the mandrel determine the form of the bundle and compact the strands composing the same so that a solid mass of scrap ready for transportation is produced. During the winding and compacting operation the sleeve 26 is shifted to the position represented in Fig. 5, and as said sleeve is of square or rectangular contour on its inner surface it fits over the like surfaces of the hub 12 and bearing 2' and locks said hub against movement. While the means shown are preferable for accomplishing this result it is distinctly to be understood that other means may be employed as substitutes therefor, without departure from the invention.

After the bundle has been formed it is rolled around in the yoke by the mandrel, and the outer surface thereof is polished and the strands are compacted into a solid ball with no projecting peripheral edges or surfaces ready for discharge from the mandrel. To accomplish this discharge the sleeve 26 is moved from the position illustrated in Fig. 5 to that shown in Fig. 3, thereby releasing the hub 12 of section 15 of the yoke, so that the friction of the ball against the interior surface of said yoke will unscrew said hub, and cause it to travel longitudinally of the shaft 5, and thus push the ball along the inclined surface of the mandrel 6, releasing it therefrom; after which by detaching the section 18 of the yoke in the manner above described, the ball or bundle may be readily removed from said mandrel.

To place the machine in condition for a renewal of the operation, pulley 35 is released by the means shown, or by other means, and is permitted to run idly upon the driving-shaft, after which the yoke is grasped by hand and the hub 12 thereof is run back upon the threaded section of the bearing, and is locked in place thereon by shifting the sleeve 26 to the position illustrated in said Fig. 5.

When a new charge of scrap is to be added to the bundle in process of formation, all that it is necessary to do is to connect one or more of the strands with those of the coil or bundle, and to then set the machine in operation in the manner described. In this way scrap merely thrown into a commingled or interlaced mass upon the floor of the mill may be readily formed into a compact bundle, and discharged from the machine at a minimum expense of time and labor.

Changes may be made in the various details of the machine, and other devices for rotating the mandrel, and for controlling the formation of the bundle may be substituted for those shown without departure from the invention, which is not limited to the precise devices shown and described.

Having thus described my invention, what I claim is—

1. A machine for bundling scrap, comprising a rotary mandrel, and a yoke into which the mandrel passes, said yoke serving to control the formation of the bundle, and to compact the same upon the mandrel.

2. A machine for bundling scrap, comprising a mandrel for winding the scrap into a bundle, a sectional yoke into which the mandrel passes, and means for securing the sections of said yoke.

3. A machine for bundling scrap, comprising a rotary mandrel upon which the scrap is wound, a yoke for defining and limiting the formation of the bundle, and means for locking said yoke against movement until the bundle is completed.

4. A machine for bundling scrap, comprising

ing a rotary mandrel for winding the scrap, a normally stationary device into which said mandrel is inserted, said device controlling and defining the formation of the bundle, 5 and means for shifting said device to eject the bundle from said mandrel.

5. The combination, with a rotary mandrel, of a bearing in which said mandrel is mounted; a sectional yoke mounted on said bearing; and means for locking the yoke to, 10 and releasing it from, said bearing.

6. The combination, with a rotary mandrel, of a bearing in which the mandrel-shaft is journaled; a sectional yoke, the hub of 15 which is mounted upon the bearing; and means for preventing movement of said yoke while the bundle is being formed.

7. In a machine for bundling scrap, the combination, with a rotary mandrel tapered 20 longitudinally, of a bearing in which the mandrel is journaled; a yoke into which the mandrel is inserted; and means for holding said yoke stationary during the bundling operation, and for releasing it after the bundle 25 has been formed.

8. In a scrap-bundling machine, the combination, with a tapering mandrel, of a sectional yoke into which the mandrel passes; a bearing upon which the yoke is threaded; 30 means for locking the yoke to, and releasing it from, said bearing; and means, including clutch-mechanism, for rotating said mandrel.

9. In a scrap-bundling machine, the combination, with a rotary mandrel provided 35 with means for engaging a strand or strands of scrap, of a device surrounding said mandrel, and cooperating therewith in the formation of the bundle; and means whereby said bundle may be released from the mandrel.

40 10. In a scrap-bundling machine, the combination, with a rotary mandrel upon which the scrap is wound, of a device for confining and compacting the bundle; means for normally locking said device against movement; 45 and means whereby said device may, when released, be shifted longitudinally of the mandrel, to discharge the bundle from said mandrel.

11. In a scrap-bundling machine, the combination, with a sectional yoke having a hub; 50 of a rotary mandrel; a support for the hub of said yoke; means for detachably uniting the yoke-sections; and means for shifting the yoke upon its support, to discharge the bundle from the mandrel.

12. The combination, with an externally-threaded bearing, of a shaft mounted in said bearing; a mandrel carried by said shaft; a yoke in which the mandrel is supported, said 55 yoke having an internally-threaded hub; and means for locking and releasing said hub.

13. In a scrap-bundling machine, the combination, with a rotary mandrel, of a sectional yoke into which the mandrel passes; 60 means for securing the sections of the yoke; a

hub projecting from one section of the yoke; a support for said hub; means for locking the hub to, and releasing it from, its support; and means whereby the hub and yoke may be shifted longitudinally of the mandrel, to 70 discharge a bundle therefrom.

14. The combination, with a bearing having an externally-threaded periphery, and adjacent to said periphery an angular surface, of a sleeve conforming on its inner wall 75 to said angular surface; a mandrel mounted in said bearing; a sectional yoke, one part of which has an internally-threaded hub provided with an angular external surface; a bearing in the other section of the yoke, to 80 receive the end of the mandrel; and means for clamping and releasing the yoke-sections.

15. The combination, with a rotary mandrel having means for the attachment of scrap to be wound, of a yoke into which the 85 mandrel passes, and by which one end of said mandrel is supported, the inner wall of said yoke serving to compact the bundle of scrap upon the mandrel.

16. The combination, with a longitudinally-tapered mandrel, having a slot for the reception of the end of a strand of scrap, of a sectional yoke for supporting one end of said mandrel; means for clamping the sections of the yoke together; means for normally locking 95 the yoke against movement, and for releasing the same; and means whereby said yoke may be shifted to eject the bundle from the mandrel.

17. The combination, with a yoke composed of sections, one of which is movable with relation to the other, of means for locking and releasing the movable section; means for normally supporting the yoke against rotation, and for releasing the same; 100 a mandrel; and means whereby the friction of the bundle against the inner wall of the yoke will cause said yoke to move longitudinally and discharge said bundle.

18. The combination, with a mandrel, and with means for rotating said mandrel, of a yoke into which the mandrel passes; and means for permitting movement of one of said elements with relation to the other, to discharge the bundle from said mandrel. 110

19. In a scrap-bundling machine, the combination, with a rotary mandrel, of a yoke through which said mandrel passes, said yoke serving to limit the size of the bundle, and to compact the constituents of the same; 120 and means actuated by the friction of the bundle against the inner wall of the yoke for shifting said yoke longitudinally of the mandrel.

20. In a scrap-bundling machine, the combination, with a rotary mandrel of angular shape in cross-section, said mandrel having a slot, of a yoke surrounding the mandrel; and means for shifting said yoke longitudinally of the mandrel. 125

21. The combination, with a longitudinally tapered mandrel having a slot, said mandrel being of angular shape in cross-section, of a yoke surrounding the mandrel; 5 means for normally holding the yoke stationary, and for releasing the same; and means whereby said yoke may be shifted longitudinally of the mandrel.

22. In a scrap-bundling machine, the combination, with a rotary mandrel, of a bearing in which said mandrel is journaled; gearing including starting and stopping mechanism for actuating the mandrel; a yoke mounted upon the bearing; and means for locking and 15 releasing said yoke.

23. The combination, with a longitudinally-tapering mandrel of angular shape in cross-section, said mandrel having a slot, of a sectional yoke provided with a bearing for 20 the reception of one end of the mandrel; means for locking and releasing the sections of the yoke; a surface upon which the yoke is threaded; and means whereby the yoke may be shifted longitudinally of the mandrel 25 when the bundle is completed.

24. In a scrap-bundling machine, the com-

bination, with a bearing having threaded and angular external surfaces, of a mandrel, the shaft of which is mounted in said bearing; a yoke having a hub threaded upon the bearing, said hub having an angular external-surface; a sleeve mounted for sliding movement upon the angular surfaces of the bearing and yoke; means for shifting said sleeve; a gear secured to the mandrel-shaft; 30 a driving-shaft; a gear on said driving-shaft, and in mesh with the gear on the mandrel-shaft; a belt-pulley; and means for clutching said belt-pulley to the driving-shaft. 35

25. A machine for bundling scrap, comprising a rotary mandrel for winding the scrap, and a normally-stationary device co-operating with the mandrel, said device controlling and defining the formation of the bundle. 40

45 In testimony whereof I affix my signature in presence of two witnesses.

DAVID B. MARWICK.
